UNITED STATES PATENT OFFICE.

CHARLES WESLEY RICHARDSON, OF PIKETON, OHIO.

RAIL-FASTENER.

1,345,958.

Specification of Letters Patent.

Patented July 6, 1920.

Application filed August 13, 1919. Serial No. 317,211.

To all whom it may concern:

Be it known that I, CHARLES WESLEY RICHARDSON, a citizen of the United States, residing at Piketon, in the county of Pike 5 and State of Ohio, have invented certain new and useful Improvements in Rail-Fasteners, of which the following is a specification.

The invention relates to a concrete rail-10 way tie, and more particularly to the class of rail fasteners for use with concrete ties.

The primary object of the invention is the provision of a tie of this character, wherein the body thereof is made from concrete and 15 reinforced, the body being cut away to provide recesses in its upper face to accommodate housings for receiving wood blocks upon which rest the track rails, the latter being fastened firmly and securely to the tie 20 in a novel manner so as to avoid any possibility of the spreading of the rails or the working loose thereof from the ties, the wooden blocks being designed to serve as 25 cushions for the rails of the track to absorb shocks and jars incident to the travel of cars thereover.

Another object of the invention is the provision of a tie of this character wherein the rail fasteners can be securely held without 30 any possibility of the fasteners working loose, with the result that the rails of the track would likewise work loose from the ties and the consequent spreading of the rails or the turning over of the same when 35 burdened with loaded rolling stock traveling thereover.

A further object of the invention is the provision of a tie of this character, wherein the cushioning block, which is preferably 40 made from wood is held within a housing seated within the tie at the top thereof, the housing and block being held against displacement through the medium of the fasteners which connect the rail and secure the 45 same upon the ties, the fasteners being of novel form so as to permit the easy placing of the same or removal when occasion requires.

A still further object of the invention is 50 the provision of a tie of this character, which is extremely simple in construction, capable of standing climatic changes, very reliable and efficient in its purpose, free from any decaying action, strong, durable, and inexpensive to manufacture and install.

With these and other objects in view, the

invention consists in the features of construction, combination and arrangement of parts, as will be hereinafter fully described, illustrated in the accompanying drawings, 60 and pointed out in the claims hereunto appended.

In the accompanying drawing:

Figure 1 is a fragmentary side elevation of a tie constructed in accordance with the 65 invention showing a track rail fastened thereto.

Fig. 2 is a vertical transverse sectional view through the tie.

Fig. 3 is a perspective view of adjunct 70 parts of the fastener disassembled.

Similar reference characters indicate corresponding parts throughout the several views in the drawing.

Referring to the drawing in detail the 75 railway tie comprises a body a portion thereof of designated A, preferably made from concrete or other cementitious substance molded or otherwise formed simulating the ordinary wood tie and having embedded 80 therein reinforcing irons B which are disposed longitudinally of the body A of said tie to materially strengthen the same.

In the upper face of the body A of the tie at the required distance from each end 85 thereof is formed a transverse recess which opens through the top face and opposite sides of said body and is adapted to accommodate a casting in the form of a U-shaped plate or housing 5, the latter being of a size 90 to snugly fit within the recess so that the ends of said plate or housing are flush with the sides of the body and likewise the upper edges of the side walls of said housing or plate will be flush with the top face of the 95 body of the tie. Removably fitted within the housing or plate 5 is a block 6, preferably made from wood, although the same may be made from any other fibrous material or from rubber, the block being of a 100 size to snugly fit within the housing or plate 5 and upon the upper face thereof rests the base of the rail 7 of a track so that said rail will be cushioned to absorb all shocks and jars incident to the travel of rolling stock 105 thereover.

The housing or plate 5 adjacent to the sides thereof has diagonally disposed circular openings 8 each adapted to accommodate a screw spike 9 having the usual head 110 to overhang the base of the rail 7, while the opposite end portion of said spike 9 is

formed with screw threads 11 for receiving a nut 12, the spike 9 being passed downwardly through a suitable hole formed in the body A of the tie when positioned for 5 securing the rail 7 upon said tie. Formed in the inner face of each side wall of the housing or plate 5 is a keyway 13 which at its upper end merges into a notch 14 opening through the top edge and outer face of the 10 side of said housing or plate and also formed in the spike 9 is a key way 15 which is adapted to register with the key way 13 in the side of the housing or plate 5, the key way 15 being extended upwardly through the head 15 10 of said spike 9 and into which is adapted to be inserted a key 16, which after the placing of the spike 9 in the hole 8 in the housing or plate 5 and through the body A of the tie is adapted to be driven into the 20 key ways 13 and 15 so as to securely fasten the spike in place. The under face of the body A below the housing is provided with suitable recesses, each being adapted to accommodate the nut 12 when engaged on the 25 threaded end 11 of the spike 9, so that the latter cannot be withdrawn from the body of the tie without the removal of the nut 12 from the threads 11 of said spike. The key 16 at its outer or upper end is formed 30 with a nib or lateral extension 17 which is adapted to be received in the notch 14 when the said key 16 has been driven home in the key ways 13 and 15 in the housing and spike, respectively.

35 The block 6 in each side edge thereof is formed with a suitable cutaway portion 18 for accommodating the spike 9 when passed through the housing or plate 5 and the body A of the tie. Thus it will be seen that the 40 spikes 9, there being two in number as shown in Fig. 1 of the drawing for fastening the rail 7 upon the tie A, are placed in position by passing the same through the housing or plate 5 and the body A of the tie, will 45 firmly and securely fasten the rail 7 upon the block 6, which latter together with the housing or plate 5 will be securely held against displacement in said tie. The key 16 when driven in the key ways 13 in the housing 50 or plate 5 and the key ways 15 in the spike 9 will make fast the said spike 9 to prevent rotation and any play which would result in the working loose of the said spike and the consequent spreading of the rail 7 when 55 secured upon the tie.

It will be clearly apparent that the spikes 9 can be readily removed from the body A of the tie and that when the spikes are in position they will firmly and securely hold the 60 rail 7 fast upon the body A of the tie so as to avoid any possibility of the spreading of the rail or the working loose thereof or the loosening of the spikes resulting from vibrations or jars incident to the travel of 65 the rolling stock upon the rail.

From the foregoing it is thought that the construction and manner of use of the tie will be clearly understood and therefore a more extended explanation has been omitted.

What is claimed is:

1. The combination with a tie made from cementitious material having a recess in its upper face, of a casting forming a housing seated within the recess and having openings in its bottom and also provided with 75 vertical key ways merging into said openings, a block held within the housing, rail fastening members passed through the block, housing and tie and each having a key way for registration with the key way in the 80 housing, and a key removably fitted in the key ways in the housing and rail fastening member respectively.

2. The combination with a tie made from cementitious material having a recess in its 85 upper face, of a casting forming a housing seated within the recess and having openings in its bottom and also provided with vertical key ways merging into said openings, a block held within the housing, rail 90 fastening members passed through the block, housing and tie and each having a key way for registration with the key way in the housing, and a key removably fitted in the key ways in the housing and rail fastening 95 member respectively, and means engaged on the rail fastening members to secure the same in the tie.

3. The combination with a tie made from cementitious material having a recess in its 100 upper face, of a casting forming a housing seated within the recess and having openings in its bottom and also provided with vertical ways merging into said openings, a block held within the housing, rail fastening 105 members passed through the block, housing and tie and each having a way for registration with the way in the housing, and means removably fitted in the ways, in the housing and rail fastening members.

4. The combination with a tie made from cementitious material having a recess in its upper face, of a casting forming a housing seated within the recess and having openings in its bottom and also provided with vertical key ways merging into said openings, a block held within the housing, rail fastening members passed through the block, housing and tie and each having a key way for registration with the key way in the housing, a key removably fitted in the key ways in the 115 housing and rail fastening member respectively, means engaged on the rail fastening members to secure the same in the tie, reinforcements inserted within the tie, and a nib formed on the key and seated within the housing.

5. The combination with a casting forming a housing adapted to be seated in a railway tie, and having vertical ways in oppo- 130

site sides, of a block carried in the housing, rail fasteners passing through the housing and block to engage a rail when upon the block, and means engaged in the ways and 5 fasteners to prevent rotation of the latter and any play thereof.

6. The combination with a casting forming a housing adapted to be seated in a rail-way tie and having vertical ways in oppo- 10 site sides, of a block carried in the housing, rail fasteners passing through the housing

and block to engage a rail when upon the block, means engaged in the ways and fasteners to prevent rotation of the latter and any play thereof, heads formed on the fasteners to engage the base of a rail, and means 15 engaged on the fasteners to secure the same in the tie.

In testimony whereof, I affix my signature hereto.

C. WESLEY RICHARDSON.
